UNITED STATES PATENT OFFICE.

JOHN M. B. SILL, OF DETROIT, MICHIGAN.

MAP-DRAWING.

SPECIFICATION forming part of Letters Patent No. 280,965, dated July 10, 1883.

Application filed April 13, 1883. (No model.)

To all whom it may concern:

Be it known that I, JOHN M. B. SILL, of Detroit, county of Wayne, State of Michigan, have invented a new and useful Improvement 5 in the Art of Map-Drawing; and I declare the following to be a full, clear, and exact description of the same, such as will enable others skilled in the art to which it pertains to make and use it, reference being had to the accompanying drawings, which form a part of this specification.

My invention consists in an improvement in the art of map-drawing, hereinafter more fully described, and pointed out in the claims.

15 In the drawings, Figure 1 is a plan view illustrating my improved guide-point tablet. Fig. 2 is a view in which guide-points and border-indicating marks are connected, thereby constituting an explanatory chart.

20 Heretofore systems of map-drawing which have been introduced have been found to be complex and cumbersome, and for this reason it has been found difficult, to a considerable degree, to instruct pupils in map-drawing by said systems. It is acknowledged by instructors generally that map-drawing is very essential in acquiring a knowledge of geography, and to this end a system is needful which shall avoid the distortion liable to occur in free-hand drawing—a system simple, easily understood by the pupil, and quickly acquired and taught. Moreover, many plans in common use have been found too expensive for efficient usefulness, and a system is demanded which 35 shall not only embody the requisites already mentioned, but shall at the same time be so economical as to admit of general use. It is evident that in the use of any system a knowledge of map-drawing must be obtained and 40 facility gained therein by repeated practice, and consequently it is essential that this practice may be secured without destroying the facilities and guides furnished to the pupil.

It is the object of my invention to overcome the difficulties named, and to provide an improved system which shall embody and furnish these essential requisites. I accomplish this object as follows:

First, I provide what I term a "guide-point 50 tablet," the tablet itself provided with an "erasable surface," preferably upon both its sides, and also with indelible guide-points, by con-

necting which suitable guide-lines will be formed for drawing the desired map. The tablet will be provided with two or more sets 55 of guide-points, each set differing from other sets upon the same surface, one set of said points answering as guide-points for drawing the guide-lines of one country, while another set of said points serves to guide the pupil in 60 drawing the guide-lines of some other country or State. I provide said tablets also with suitable corner marks or points, by connecting which a suitable border-line is provided for a given map. I design to construct said tablets, 65 or each erasable surface thereof, with suitable explanations of the guide-points, so that the pupil will easily understand what kind of 70 guide-points to connect in order to have the guide-lines for the map desired. The corner marks may be different on the same surface for the border-lines of different maps; or they may, for sake of simplicity, be alike, as their location horizontally and perpendicularly to each other will readily indicate what corner 75 marks to connect for the border-line desired. To this end, as illustrated in Fig. 1, two dashes at right angles to each other, and a star or other guide-points in the angle so formed, designate the northeast corner, and two dotted 80 lines at right angles to each other, and containing a guide-point in the angle so formed, represent other corners to guide the drawing of the border-lines. A system of dots represents the guide-points for drawing the 85 guide-lines for a map of Europe. A system of crosses represents the guide-points for drawing the guide-lines of a map of North America. A system of stars represents the guide-points for drawing the guide-lines of a map of South 90 America, while a system of different guide-points may serve to guide the pupil in drawing the guide-lines of any other desired country. The tablet is provided with a number 95 of different sets of guide-points for drawing the guide-lines of different maps. These guide-points, being made small, will not interfere with the general outline of any given map, nor serve to confuse the pupil, as all that is required to do in drawing any desired map is, 100 first, to connect in order the guide-points designated for that purpose in the explanations with which the tablet is provided. When this practice has been completed and a different

map is desired, the one already drawn may be erased, the guide-points still remaining, and another may be drawn upon the tablet, the same tablet and the same system of guide-points serving for practice during the entire course of the pupil in map-drawing for said countries, or until he has become perfectly familiar with the outlines of said countries.

In order to make this system more complete, and more easily acquired and taught, I design also to provide, second, an explanatory chart, on which the guide-points illustrated in Fig. 1 shall be suitably connected by the desired guide-lines, as illustrated in Fig. 2. This tablet serves as a pattern or copy for the pupil to follow in connecting the guide-points upon his erasable tablet to form the desired guide-lines for any given country, the second tablet in itself explaining and illustrating the operation desired of the pupil upon his guide-point tablet. Moreover, it is often found desirable in reviews, examinations, and for other purposes to have maps of various countries drawn by the pupil in permanent form upon paper to preserve for exhibition, for which the erasable tablet is not so well adapted. To this end I design to construct the explanatory chart as a stencil-chart; also, I construct said chart with the guide-points, corner-marks, guide-lines, and boundary-lines, &c., to serve the purposes of explanation, as already mentioned, the construction being such that when it is desired, for the purpose of drawing maps upon paper, to make it a stencil as well as an explanatory chart, perforations may be made with a pin or other suitable instrument through the center of each guide-point; or these perforations may be made when the chart is manufactured. Then, by laying the chart upon the paper upon which the map is to be drawn, the guide-points for any country may be made by dotting the paper, through the holes thus made, with a sharp pencil-point or otherwise. I therefore call this second device (illustrated in Fig. 2) a "stencil and explanatory chart," said chart designed to accompany my improved guide-point tablet, said chart containing in substance the requisite explanations of the purposes for which it is designed. This chart, it will be seen, is adapted to be made of permanent use, as it will readily serve for any desired length of practice of the pupil upon the countries embraced thereon, all that is requisite for the pupil being a set of maps constructed with similar guide-lines, and a set of guide-point tablets

having an erasable surface, and a set of stencil and explanatory charts, each of which tablets and charts answers for the maps of several countries. It is evident, therefore, that my improved system is an economical one, while 60 it is clearly comprehensible and may be easily followed. The guide-points are arbitrary points, said points being represented by any desired mark, the guide-lines also being arbitrary in their nature, only being such as to 65 readily and efficiently serve the purpose for which the guide-lines are used.

I would have it understood that I do not confine myself to any particular form of guide-points or any particular location thereof, or 70 any particular configuration of the guide-lines, as any suitable guide-point might be used. They might be located at any suitable points, and the guide-lines might form an entirely different configuration from those illustrated in 75 the accompanying drawings.

For greater clearness I design to construct the stencil and explanatory chart with guide-lines for different countries, varying from each other in appearance, as shown in Fig. 2, said 80 variation of appearance being in the different coloring of the lines, or of any other obvious difference of construction, so that the guide-lines upon said chart for different countries will not be confused with each other. The 85 maps provided for by this system of guide-points on each surface of the erasable tablets, it will be seen, will be drawn on the same scale.

I would have it understood that I design to include in the term "chart" its use as a stencil to guide the pupil in fixing guide-points upon another surface, for the purpose already indicated. Said chart may be made of any suitable material, and also the tablet.

What I claim is—

A tablet with an erasable surface, provided with a series of similar and dissimilar guide-points, each series of similar guide-points adapted to be connected by straight lines to form a diagram to aid in drawing a map-out-line, and all of said diagrams forming the appropriate outlines of several maps, substantially as described.

In testimony whereof I sign this specification in the presence of two witnesses.

JOHN M. B. SILL.
